UNITED STATES PATENT OFFICE.

LEONARD HENKLE, OF ROCHESTER, NEW YORK.

PANEL FOR DOORS.

SPECIFICATION forming part of Letters Patent No. 364,252, dated June 7, 1887.

Application filed May 10, 1886. Serial No. 201,662. (No model.)

To all whom it may concern:

Be it known that I, LEONARD HENKLE, of the city of Rochester, in the county of Monroe and State of New York, have invented a certain new and useful Improvement in Panels for Doors; and I do hereby declare that the following is a full, clear, and exact description of the same, reference being had to the drawings accompanying this application.

10 My improvement relates to doors having panels made of sheet metal, in place of the wooden panels ordinarily used, the design being to secure cheapness with ability to stamp up or out on the panels ornamental designs in relief, and such as cannot be produced on wood without great expense.

15 The invention consists of a panel composed of two plates of sheet metal struck up with any suitable design, or made plain and straight, 20 fitted back to back, and soldered or otherwise attached together, the edges being swaged outward to form sockets to receive the edges of the wood-work, all as hereinafter described.

25 In the drawings, Figure 1 is a face view of one of the panels. Fig. 2 is a longitudinal cross-section of the same in line $x-x$ of Fig. 1. Fig. 3 is a face view of a wooden door with four of the metal panels set in place. Fig. 4 is an enlarged cross-section of a portion of Fig. 30 3 in line $y-y$.

35 The panel is made of sheet metal—such as galvanized iron—and in two plates, A A. These plates are struck out with any suitable ornamental design, as shown at $a-a$; or, if desired, left straight and plain in the center. The edges $b-b$ all around are swaged out, forming sockets $c-c$, of square, rounded, or beaded form, and of sufficient size to receive the edges of the rails and cross-pieces of the 40 wooden door. When thus prepared, ready for attachment to the door, the plates are placed back to back, as shown in Fig. 2, and soldered or otherwise attached together at the flat meeting portions, thus making one integral body.

45 B indicates the door, consisting of the ordinary rails and cross-pieces. When the parts of the door are framed together, the metallic panels are framed into it, the edges of the wood fitting closely in the sockets $c-c$ of the 50 panels, and the flanges $b-b$ of the panels overlapping the edges of the wood and fitting closely thereto. The metal being thin and being closely fitted to the wood, presents an ornamental appearance. They can be painted 55 or stained to correspond with the wood, or

they can be ornamented in any desired manner in contrast thereto.

Among the advantages of this invention is, the metal panels are cheaper than wood panels, and can be applied with much less labor. 60 The panels are stronger than wooden panels, and will not split or break out. The overlapping edges cover the joints of the wood and prevent the unsightly appearance that occurs from the opening of the joints in wood 65 panels under expansion and contraction. One of the most important advantages is that when dies are made, large numbers of the panels can be struck out with great rapidity and but little labor, while in wood the panels, if made 70 with ornamental designs, would have to be made with carvings, which, in elaborate designs, would be very expensive.

The double thickness of the panels gives them great stiffness. The embossing or striking out of the panels, in addition to producing ornament, stiffens them and gives them strength.

Having described my invention, what I claim as new, and desire to secure by Letters Patent, is—

1. The panel for doors herein described, consisting of two metallic plates having their edges swaged out to form sockets to receive the wood-work of the door, said plates being 85 placed back to back and soldered or otherwise secured together, as set forth.

2. The panel for doors herein described, consisting of two metallic plates having their edges swaged out to form sockets to receive 90 the wood-work of the door, and the center portion struck out to form ornamental designs and to stiffen the panel, said plates being placed back to back and soldered or otherwise secured together, as set forth.

3. The combination, with a door, of metallic panels each consisting of two plates fitted back to back and secured together, the edges forming sockets that receive the edges of the wood-work, said edges of the panels overlapping the joints of the wood, as herein shown 95 and described.

In witness whereof I have hereunto signed my name in the presence of two subscribing witnesses.

LEONARD HENKLE.
